E. JONES & J. HALL.
COAL CUTTING MACHINE.
APPLICATION FILED SEPT. 17, 1908.

928,056.

Patented July 13, 1909.

UNITED STATES PATENT OFFICE.

EBENEZER JONES, OF MARTINS FERRY, AND JOHN HALL, OF MAYNARD, OHIO.

COAL-CUTTING MACHINE.

No. 928,056.

Specification of Letters Patent.

Patented July 13, 1909.

Application filed September 17, 1908. Serial No. 453,434.

To all whom it may concern:

Be it known that we, EBENEZER JONES and JOHN HALL, citizens of the United States, residing, respectively, at Martins Ferry and 5 Maynard, in the county of Belmont and State of Ohio, have invented a certain new and useful Improvement in Coal-Cutting Machines, of which the following is a specification.

10 This invention relates more particularly to that class of coal mining machines known variously as undercutting chain breast or long wall machines.

The object of the invention is to simplify 15 and cheapen the construction, to make it more reliable and durable in use, and less liable to derangement, to render its repair more expeditious and less costly than those at present in use.

20 The invention is embodied chiefly, first, in improved means for articulating cutter bit holding blocks; second, improved means for facilitating the addition of links or bit blocks to or their removal from a cutter chain while 25 on its supporting frame, and, third, in an improved form of bit holding block, or as herein shown, described and claimed, the invention not being confined in its practical embodiment to precisely the forms of parts shown.

30 In the accompanying drawings illustrating said embodiment of the invention—Figure 1 is a plan view with a portion of the cutting chain removed from the sliding or carrying frame; Fig. 2 is a detail view on a scale, 35 larger than in Fig. 1, of the outer or cutting edge of the chain; Fig. 3 is a cross section on the line $x-x$, Fig. 1, through the chain and guide showing that section of the chain guide where the outer portion is made removable 40 to permit the removal of cutter bit holding blocks and links; Fig. 4 is a section on the line $y-y$, Fig. 2, through a cutter bit holding block taken longitudinally with reference to the chain and showing in full view portions 45 of links. Fig. 5 is an edge view of a link. Fig. 6 is a cross section of the cutter head on the line $z-z$, Fig. 1. Fig. 7 is a cross section of the chain guide showing an auxiliary guide to steady the chain as it leaves the driving sprocket wheel. Fig. 8 is a diametrical section of a sprocket wheel employed in the 50 construction.

The sliding frame, as usual, in under cut-

ting or breast machines, is of isosceles triangle 55 form, but in the present instance the head is composed of a casting 9 to which is bolted the corresponding chain guide 1. The chain guide 1 has a base 1^a and a head 1^b with an intermediate web 1^c. It is therefore shaped in cross section somewhat like an ordinary 60 railroad rail or I-beam, the base of the guide at the head of the sliding frame being secured to the head by bolts and nuts as seen at 9^a. The base of the guide at the head is made with a tongue 9^b that fits in a corresponding groove in the head, said tongue aiding in strengthening the connection between the head and guide. It will be observed that viewed without the base or inner portion of the I-beam the guide is of T-form. 70 7 designates the back end or apex casting, 75 of the sliding frame, and the side chain guides are secured to tongues on the apex and base castings, 7 and 9 respectively, by bolts and nuts as illustrated at 10. The side chain guides are of substantially the same form in cross section as the chain guides at the head of the sliding frame. The side chain guides are each made in two principal parts divided at 11, the contiguous ends being provided 80 with slotted lapping tongues 5 held together in adjusted position by bolts as seen at 5^a. The side chain guides spring a little when the parts of the sliding frame are adjusted from or toward each other and with respect to the 85 normal position, and the guides are thus kept in substantial alignment. The frame is shown to be braced in the perpendicular of the triangle by T-bars 12 fixedly secured by bolts 12^a to the forward or base piece 9, said bars being adjustably secured by bolts 12^b to slotted tongues 7^a on the apex piece 7. A section 1^{bb} of the head portion of a side guide can be made removable by means of a set 90 screw 1^c (see Fig. 3), or several of them so that cutter bit blocks can be removed from or added to cutter chain.

The cutter bit block is, generally speaking, 100 of U-form in cross section, but with laterally projecting outer corners as seen at 2¹. The bit block straddles the outer portion of the guides and each leg 2 of the block is formed with an upwardly projecting thickening boss 2^a and with two ears 2^b, the latter being provided with perforations or bearings 105 2^c. The outer or leg-connecting portion of

The sliding frame, as usual, in under cut-

the block has rounded edges, as seen at 2^a, (see Fig. 4). The blocks are connected together to form a chain by straps or links 3, (see Fig. 5), each having pins 3^a that enter 5 the perforation of bearing 2^c, of the ear 2^b, and each link has a boss or thickened portion 3^b near its middle. The links 3 lie between the legs and the web of the guide and they and the bosses 2^a travel in the cavities at the 10 sides of the chain guides and the blocks are held from running off the guides by the links, and by the bosses 2^a also if desired. In case the cutters are worn down the laterally projecting outer corners 2^d insure a cut wider 15 than the thickness of the sliding frame and therefore freedom of movement of the frame in the cut or kerf.

4 designates the sprocket wheels suitably journaled in the castings at the corners of the frame. The sprockets of these wheels are adapted to project between the outer or leg-connecting portions of the blocks and bear against the rounded edges of said portions. These sprocket wheels also having lateral 25 shoulders 4^a on which the legs of the cutter holding blocks and the links run as the chain passes around the corners of the frame. The castings at the corners are shown as so formed that the shoulders 4^a of the sprocket 30 wheels, project somewhat beyond the castings as shown, so that the said legs and links will run on the shoulders and not on the castings. Friction in operating the chain is thereby lessened and the castings and parts 35 saved from wear. The sprocket wheels can also be cupped as seen at 4^b at their upper sides to receive a lubricant and channels 4^c provided from the cup to the bearings. The characters 2^d, 2^e, and 2^f respectively designate 40 pairs of cutter bits in three successive blocks. The bits in each pair can be arranged at graduated distances apart. The bits of the first pair in the series of three being farthest apart, and the last the least separated. This particular arrangement of bits 45 promotes the disintegration of the coal lying in the path of the teeth and steadies the operation of the chain, one row balancing the other. As is more customary, a single bit 50 can be secured in each block, if desired. The bits are removable and are secured by set screws 2^g as usual. The shank of the bit is secured to stand at an incline to the direction of its path and the block back of the bit is 55 braced by an extension 2^h. The sprocket at the rear or apex of the frame is the driving sprocket, and to retain and steady the chain as it comes from this sprocket we provide a sheet metal guide 8 secured at one edge by 60 bolts 8^a to the apex casting and having the other portion reaching out and around to a line beyond the path of the teeth or one row of the teeth, as seen in Figs. 1 and 7.

Among numerous advantages of our construction are that the chain is securely held

in its path, it has large bearing surfaces, it can be economically and quickly repaired, and there is no liability of the sliding frame to stick in the kerf made.

What we claim and desire to secure by Letters Patent is:

1. In a cutting mechanism for mining machines, the combination with a frame provided with a suitable guide, of a cutting chain to travel on said guide comprising bit blocks of U-form and links connecting the legs of said blocks, said links lying between the guide and the said legs. 75

2. In a cutting mechanism for mining machines, the combination with a frame provided with a guide having a T-shaped outer portion, of a cutting chain to travel on said guide comprising bit blocks of U-form having their legs provided with bearings, and links provided with outwardly projecting pins or 80 studs connecting the blocks by engagement of said pins or studs with said bearings, said links lying between the web of the guide and the legs of the bit blocks. 85

3. In a cutting mechanism for mining machines, the combination with a frame or cutter head and cutting chain support or guide thereon, of a cutting chain comprising cutter-bit holding blocks having their opposite sides at their outer portions projecting laterally 95 beyond the horizontal planes of the sides of the chain support and formed with angular cutting corners which lie in substantially the same vertical plane, the sides forming said cutting corners being planes at angles to a 100 horizontal plane. 90

4. In a cutting mechanism for mining machines, the combination of a sliding frame provided with a chain guide of I-beam form in cross section, a cutting chain to travel 105 thereon including bit holding blocks of U-form having their legs provided with inwardly extending bosses to project between the base and head portions of said guide, and links confined between the web of said guide and the said legs and connecting said blocks. 110

5. In a cutting mechanism for mining machines, the combination of a sliding frame provided with a chain guide having an outer portion of T-form in cross section, a cutting 115 chain to travel thereon including bit holding blocks of U-form having their legs provided with perforations constituting bearings and links provided with pins to engage said perforations to connect said blocks, said links being confined between the web of said guide and the legs of the bit blocks, a portion of the guide being removable to permit the putting on and taking off from the guide of the blocks and their connecting links. 120

6. In a cutting mechanism for mining machines, the combination of a cutter chain supporting frame and a suitable guide thereon upon which the cutter chain travels, and a cutter chain on said guide including cutter 130

bit holding blocks provided with suitable seats for removable cutter bits, said cutter bit holding blocks having their opposite sides projecting beyond the horizontal planes of the corresponding sides of both the guide and frame, whereby a clearance in the kerf for said frame and guide in rear of said blocks

is provided in case the bits in said blocks are worn off.
